DESIGN FOR A DISPLAY CONTAINER FOR
JEWELRY OR OTHER ARTICLES

John Guttman, Brooklyn, N. Y., assignor to Arrow Manufacturing Company, Inc., Hoboken, N. J., a corporation of New Jersey

Application April 16, 1935, Serial No. 56,415

Term of patent 7 years

To all whom it may concern:

Be it known that I, John Guttman, a citizen of the United States, residing at New York city, Borough of Brooklyn, in the county of Kings and State of New York, have invented a new, original, and ornamental Design for a Display Container for Jewelry or Other Articles, of which the following is a specification, reference being had to the accompanying drawing, forming a part thereof.

Fig. 2 is a front elevational view thereof.

Fig. 3 is a side elevational view thereof.

The curved surface is of contrasting color with the flat surfaces. The curved bands are made of metal having a highly polished surface.

I claim:

The ornamental design for a display container for jewelry or other articles as shown and described.

In testimony whereof I affix my signature.

JOHN GUTTMAN.
